UNITED STATES PATENT OFFICE

131,228

DESIGN FOR A WASHING MACHINE

Arthur P. Schulz, South Bend, Ind., assignor to
Bendix Home Appliances, Inc., South Bend,
Ind., a corporation of Delaware

Application May 31, 1940, Serial No. 92,707

Term of patent 14 years

To all whom it may concern:

Be it known that I, Arthur P. Schulz, a citizen of the United States, residing in South Bend, in the county of St. Joseph and State of Indiana, have invented a new, original, and ornamental Design for a Washing Machine, of which the following is a specification, reference being had to the accompanying drawing, forming part thereof.

Figure 1 is a perspective view of a washing machine showing my new design;

Figure 2 is a fragmentary top plan view on an

enlarged scale of the soap door and portions surrounding the same, taken on top near the front of the machine shown in Figure 1; and

Figure 3 is a side elevational view of Figure 2.

The design of the side of the machine not seen in Figure 1 is substantially like that of the side shown.

I claim:

The ornamental design for a washing machine, substantially as shown and described.

ARTHUR P. SCHULZ.
